SIPHON BOTTLE

Filed Dec. 14, 1927

UNITED STATES PATENT OFFICE

EMIL WEINHEIM, OF NEW YORK, N. Y.

SIPHON BOTTLE

Application filed December 14, 1927. Serial No. 240,062.

This invention relates to siphon bottles. The object of the invention is to improve in general both the mechanical construction and assemblage of the devices going to make up 5 a siphon bottle, and also the appearance of such an article. A further object of the invention is to provide for the simple and efficient charging of such a bottle, and the simple and efficient dispensing of liquid from 10 such a bottle, and for the protection of all the parts thereof for easy and safe transportation, such as when traveling. More particularly it is an object of the invention to provide improved devices for controlling both 15 the charging of the contents of such a bottle and of the discharge of the liquid contents of such a bottle.

The above and further objects of the invention will better be understood by reference 20 to the illustrative embodiment of my invention, to which the accompanying claims are directed solely for purposes of illustration and not limitation. This illustrative embodiment is described in the following specification, 25 in connection with the accompanying drawings which form a part thereof.

In the drawings, the single figure is a vertical section of a bottle which is understood 30 to be in the main fabricated of solids of revolution.

A indicates a glass jar or bottle with a large, flaring mouth, and preferably formed at the mouth with a ledge 1, adapted to seat the closure B. The flange 2 at the mouth of the 35 bottle is preferably formed with an undercut ring 3 to interlock with the sealing flange 4 of the closure B. It is preferred that the closure B be molded of some material such a bakelite, aluminum, or nickel, in which the 40 siphon tube 5, preferably provided with a flared mouth 6, may be seated during the molding or thereafter, as desired. In the embodiment illustrated, it is contemplated that the flange 4, after the application of the closure B, shall be heated and spun into intimate 45

contact with the glass flange 2, although it is also contemplated that the closure B may be seated and held to the walls of the bottle in any suitable manner.

It is preferred that a protecting metal 50 sheath C be provided for the bottle, and to this end it is convenient that it be formed in two parts, an upper part 10 and a lower part 11, engaged one with another by means of the screw thread 12. It is also preferred that 55 a cap 13, serviceable as a drinking cup, seat over the mouth of the bottle and form also a protection for the devices associated with the closure B.

The discharge spout 14 is preferably hook 60 shaped, as illustrated, and swivels in a machined perforation 15, extending through the closure B. It is sealed off at the top by a buttress ring 16, formed on the vertical portion of the spout, which preferably clamps a 65 sealing washer 17 to the top of the closure B. The inner end of the spout 14 is closed by a screw threaded plug 18, the flange 19 of which clamps the washer 20 to the under or inner face of the closure B, both to hold the 70 spout in its mechanical relation to the closure and to effect a fluid seal against the entrance of fluid into the perforation 15. The part 21 of the spout 14 within the perforation 15 is provided with a port 22 to register with a 75 duct 23 extending from over the mouth of the siphon tube 5 through the body of the closure B. The spout 14 may swivel from the discharge position shown in dotted lines to the protected position shown in full lines. 80 In the discharge position the duct and port are in communication, to permit the discharge of fluid, but in the protected position, they do not register, to permit the discharge of fluid. In addition to the closure of the valve 85 formed by the swiveling spout, a plug closure 30 is preferably provided. This plug has a threaded portion 31 taking into the threaded perforation 32 overlying the siphon tube 5. An unthreaded extension 33 carries a sealing 90

washer 34 fitting snugly, preferably cup shaped, into the machined cylindrical valve space 35, from which the duct 23 leads. When the plug 30 is screwed down, the washer 34 positively seals off the discharge mouth of the siphon tube 5. When it is backed out, it seals the opening through which the plug 30 enters the closure B, but permits an opening into the discharge duct 23.

10 For the purpose of charging the siphon bottle, a perforation 40 is formed in the closure B. The inner or distal end of this perforation is fitted with a soft rubber nipple 41, preferably substantially acorn in shape, with a flange 42 expanded into a similar configuration in the closure, while the distal end of this valve nipple has a conical formation 43. The perforation 44, through this nipple, is normally closed by the internal fluid pressure of the siphon bottle, but the nipple will permit the entrance of a charging tube such as that shown and described in my copending application, now known as Day's Docket No. 2555 and executed on even date herewith.

25 To re-enforce the closing function of the nipple 41, a screw plug 50 is provided to work in the outer end of the perforation 40, and has an inner extension 51 directly closing upon the outer end of the rubber nipple 41. The 30 finger manipulating grips shown for manipulating the plugs of my siphon bottle are of course merely illustrative of suitable means for effecting their operation.

What I claim and desire to secure by United States Letters Patent is:

35 1. A siphon bottle having a wide mouth and a platform closure; a discharge nozzle swiveled in said platform closure to occupy both an overhanging and a completely overlying position; a siphon tube and an openable and closable closure for the proximal end of said siphon tube.

40 2. In a siphon bottle, a glass bottle having a wide mouth, the lips of which mouth are internally provided with circular ribs; a platform closure for closing the mouth of said bottle formed of moldable material and at its rim having a hollow flange embracing the rim of said bottle and with an interior portion 45 upstanding from the general level of said closure and seated in the irregularities formed by said circular ribs.

45 3. In a siphon bottle, a closure, a discharge spout swiveled to said closure and having a side port within said closure; a siphon tube seated in said closure; a duct leading from the mouth of said siphon tube to said spout at the locality of said port; and a valve plug 50 screwed into said closure and directly acting upon the mouth of said siphon tube.

55 4. In a siphon bottle, a closure having a perforation; a nipple formation of soft rubber fitted into the distal end of said perforation and having a conical configuration at its distal 60 end, and an axial perforation therethrough,

closable by fluid pressure upon said distal end.

5. The structure as defined in claim 4, and further characterized by the fact that the proximal end of said perforation is screw threaded, and there is provided a screw threaded plug to engage the proximal end of said nipple to effect a permanent and positive fluid closure thereof.

70 In witness whereof, I have signed my name to this specification, this 5th day of November, 1927.

75 EMIL WEINHEIM.
